WHEELED TRAPEZE BAR

James William Gregory, 922 Hollywood Ave.,
Dallas, Tex.

Filed Sept. 13, 1960, Ser. No. 62,127

Term of patent 14 years

(Cl. D34—5)

FIG. I

FIG. II

FIG. I is a perspective view of a wheeled trapeze bar showing my new design;

FIG. II is a side elevational view thereof.

The dominant features of my design reside in the portions shown in full lines.

I claim:

The ornamental design for a wheeled trapeze bar, substantially as shown and described.
